JOURNAL OILER

Rudolph W. Miller, Winona, Minn.

Application November 23, 1934, Serial No. 754,511

10 Claims. (Cl. 308—88)

The invention relates to journal oilers and has as a provision means to replace the ordinary waste used in journal boxes to supply oil to the journal.

5 It is an object of the invention to provide a device of this character that may be assembled in the journal box while the journal is in place therein.

It is a further object of the invention to provide 10 a device of this character comprising a plurality of absorbent elements assembled in edge-wise contact with the journal having means to prevent lateral movement between the elements.

It is a further object of the invention to provide 15 a device of the character referred to having means to resiliently press the assembled elements against the journal.

It is a further object of the invention to provide 20 a device of the character referred to having means to prevent excessive compression of the fibers of the absorbent material in contact with the journal.

It is a further object of the invention to provide 25 a device of this character made up of similar elements which may be individually assembled in the journal box.

It is a further object of the invention to provide 30 a device of this character having means to prevent access of grit to the shoulders at the ends of the journal bearing surface and to lubricate such shoulders.

It is a further object of the invention to provide 35 a device of this character which will successfully withstand wear of the journal.

Further objects of the invention will appear 40 from the following description when read in connection with the accompanying drawings showing illustrative embodiments of the invention, and wherein:—

Figure 1 is a central vertical section of a journal box with the device assembled therein, the journal being shown in elevation;

Fig. 2 is a vertical transverse section on line 45 2—2 of Fig. 1;

Fig. 3 is a plan view of means for connecting the absorbent material elements into assembly and means to prevent the assembly from twisting in the box, with the absorbent elements omitted;

Fig. 4 is a plan view of one of the elements of 50 Figs. 1 and 2;

Fig. 5 is a side elevation of a single element showing another embodiment of the invention;

Fig. 6 is a section on line 6—6 of Fig. 5;

Fig. 7 is a plan view of the structure of Fig. 5;

Fig. 8 is a section corresponding to Fig. 1 of a

plurality of elements of a still further form of the invention;

Fig. 9 is a section through a journal box illustrating the manner of assembly of the device of the invention therein, and

Fig. 10 is a section corresponding to Fig. 6 of a different form of element.

As shown in Figures 1 and 2 the device is applied to a journal box 10 having a journal 11 in place therein. As there shown the device comprises a plurality of individual elements 12 which may be similar, said elements comprising bodies of absorbent material, their shape in side elevation being shown in Figure 2. As a material for these elements felt is preferred, which felt may 15 desirably be substantially one-half inch in thickness. It will be understood that each element may be made of a plurality of layers of cloth sewn together or of any other suitable absorbent material that may exist in form-retaining condition for assembly into the journal box.

It is important that, as shown, the edges of the felt elements contact the journal. One cause of hot boxes when "waste" is used as packing is that fibers adhere to the journal, as by freezing, are 25 carried under the brass and cause erosion. The same will happen if felt be used in contact with the journal at a side surface of the felt, although to a less extent than with "waste" since the felt fibers are finer. When used edgewise however a 30 preponderance of the contacting surface of the felt is composed of ends of fibers with their lengths anchored in the felt body. When so used, a maximum capillarity is had for feed of lubricant.

To allow the body of oil in the bottom of the box to flow so as to equalize itself in the box, to feed the oil to the body of the absorbent material, and to increase lateral flexibility for easy flexure of the lower portion of the absorbent mass for 40 facility of introduction thereof into the journal box in the manner described below, the legs or projections 43, shown at the bottoms of the elements, are provided preferably by cutting away 45 the material of the felt therebetween so as to preserve integrality of fibers between the projections and the body of the mass.

To prevent lateral movement between the elements when assembled in the form of Figures 1, 2, and 5, the elements are shown provided with perforations adapted to receive rods 13 upon which the elements are slipped and upon which they are retained as by means of a metal plate 14 pressed against the elements by springs 15 55

abutting against a washer 16 which may be retained as by a cotter pin 17.

The preferred manner of applying this form of the invention is to form the rods 13 integral at one end with a transverse member 18 whereby the rods 13 and the member 18 can be made from a single length of heavy wire.

To prevent the assembled device from twisting in the box, there are shown a pair of rods 19 having eyes 20 through which the rods 13 are passed, the rods 19 curving upwardly to contact at their ends an upper surface of the journal box.

To prevent the eyes from slipping around the angle between the rods 13 and the portion 18, there are shown in Figure 3 washers 21 closely fitting the rods 13 and as an additional protection from slippage, a drop of solder 22 may be placed upon the outside of the rods 13 at the ends of the portion 18.

20 The manner of assembling the described parts is illustrated in Figure 9. The eyes 20 in the rods 19 are shown as of sufficient size to allow of relative motion to such a position as shown in Figure 9 whereby they may be introduced into the journal box. The first element 12 which is slipped upon the rod 13 and pressed back into contact with portions of the eyes 20 will cause the rods 19 to be forced toward a position at right angles to the rods 13 and to assume the position shown 25 in Figure 1 whereupon the first placed element 12 and the rods 19 may be forced back in the box to their position of assembly after which successive elements 12 may be introduced in tilted position, threaded upon the rods 13 and shoved back 30 into place.

35 A serious defect in former devices which have been proposed for this service has been that they cannot be placed in the journal box where the form of door and box illustrated in Figure 1 is used, and this form of journal box has now come into almost universal use.

40 It is therefore an important object of the present invention to provide a device that can be assembled when desired into an existing journal box.

45 To press the elements 12 into edge contact with the journal, there are shown springs 23 placed in passages 24 cut out from material of the elements 12. To prevent the springs 23 from displacement 50 out of the passages 24, straps 25 are desirably placed upon each side of the elements 12 and connected together by means of rivets 26. If the springs 23 apply their pressure entirely upon the absorbent material of the elements, the continued pressure of the material against the journal will cause a hardening of the surface in contact with the journal and a consequent reduction of the capillary action of delivering oil to the journal and excess wear of the absorbent material. To prevent such an effect, rigid elements 55 27 are shown embedded in each of the elements 12. In the initial form of the elements, the members 27 stand slightly below the surface of these elements, as indicated at 28, to come into contact with the journal when some compression of the absorbent material has taken place.

60 It is preferred to make the elements 27 of wood and hard maple is a desirable variety of wood for the purpose, but it will be understood that it is 70 within the purview of the invention to use any rigid material, but desirably a material that will withstand wear by the journal.

75 In the form of the invention of Figures 1, 2, and 4, a chamber is formed in the material of the element 12 as by pressing the same upon a

circular saw, into which chamber the slab 27 of wood or the like may be placed.

5 It is desirable to provide a bushing for the elements 12 upon the rods 13 which may be provided in the form of an eyelet 29 placed through the perforations in the absorbent material and upset at its ends. If rods without bushings, or bushings loose in the felt be used, the play between metal and felt will promptly enlarge the opening in the felt rendering the springs ineffective. It is therefore of importance to use the eyelets which by their anchorage to the felt will eliminate such play. When this structure is adopted, the chamber for the elements 27 is made to extend so as to intersect the openings for the rods 13. The rigid elements 27 are placed into the chamber and partake of the perforations for the rods 13; the eyelet is placed through the absorbent material and through the rigid element 12; and the upper coil 10 of the spring 23 is desirably turned to the position illustrated in Figures 2 and 5 and is secured 15 by the upsetting of the eyelet.

20 In the above described relation of the parts, the pressure of the spring 23 is applied against the rigid element 27. If the element 27 is absent, the spring and eyelet may be similarly assembled but the pressure of the spring may be allowed to come against the eyelet. If the eyelet also is omitted, then the pressure of the spring desirably comes below the rod 13 so as to provide for a uniform spring pressure at all times upon the absorbent material. It will be understood that the springs 23 and also the rigid elements 27 may be omitted from same, even from all but two or three, of the elements 12 within the purview of the invention.

25 To press the material of the end elements 12 laterally against the shoulder 30 at the end of the journal and also against the shoulder 31 at the remaining end of the bearing surface of the 40 journal, there are shown springs 32, 33 abutting against the rigid elements 27 in the end elements 12 to press the felt outwardly against these surfaces whereby not only to oil the surfaces but also to prevent access of grit thereto.

30 In the form of Figure 5, the rigid elements 34 are shown in the form of pins, which may be of wood, and may seat upon wires 35 passed transversely through the element 12 and supported by the eyelets 29, the pins as shown desirably standing normally slightly below the journal contacting 45 surface of the element.

35 In another form of the invention shown in Figure 8, the rods 13 are substituted by pins 36 carried by plugs seated in the eyelets 29, the pins 36 being preferably tapered for ready telescoping with the eyelet of the preceding element 12 during assembly, thus providing rigid means for preventing lateral movement between the 50 elements 12. In this form of the invention the rods 19' may be assembled with the first element 12 to be inserted in the box, which element may be inserted flatwise and swung to vertical position as it approaches its location in the rear of the box.

40 In the form of Figure 10, instead of forming a pocket in the material of the absorbent plate to receive the material 27, the rigid wear-resistant material 27' is placed between two layers 41, 42 of absorbent material and the eyelet 29 may be passed through the three layers to provide an assembled element for use.

45 By the provision of the elements 12, each constituting a complete article of manufacture, they 50 may be constructed and assembled in quantity 75

and shipped to the place of installation together with an appropriate number of rods 13, 18, and of the rods 19. They may be handled each as an entity and may be assembled together in the journal box by unskilled labor.

To reduce the amount of oil fed to the journal the journal contacting surface of element 12 may be honey-combed or serrated as shown at 40, Figure 5.

10 Minor changes may be made in the physical embodiments of the invention within the scope of the appended claims without departing from the spirit thereof.

I claim:

15 1. A journal oiler comprising, in combination: a journal box; a journal therein; a rod in said box parallel with the axis of the journal; a plurality of individual, flat, absorbent elements each having a perforation engaging said rod; a plurality of plate elements of rigid, non-metallic material each having a perforation engaging said rod; said plate elements each embedded in one of said absorbent elements; said absorbent elements assembled in side by side relation transversely of said journal with their edges in contact therewith; means carried by the rod to hold the elements in assembly thereon; and resilient means reacting through said rod to press the edges of the assembled elements into contact with the journal.

20 2. A journal oiler comprising, in combination: a journal box; a journal therein; a rod in said box parallel with the axis of the journal; a plurality of individual, flat, absorbent elements each having a perforation engaging said rod; said elements assembled in side by side relation transversely of said journal with their edges in contact therewith; means carried by the rod to hold the elements in assembly thereon; resilient means reacting through said rod to press the edges of the assembled elements into contact with the journal; and rods extending from said first named rod and each abutting a surface of said box to prevent displacement of the assembly.

25 3. A journal oiler comprising, in combination: a journal box; a journal therein; a plurality of individual, flat, absorbent elements assembled in face to face relation in said box transversely of the axis of said journal; eyelets piercing the respective elements; rigid means entering adjacent eyelets and spanning the spaces between said elements; and resilient means reacting directly between said box and certain of said eyelets to press the edges of the assembled elements against said journal.

40 4. An element to be assembled in a journal box with other similar elements comprising, in combination: a form-retaining plate of absorbent material; said plate having an aperture and a recess cut in its material terminating adjacent said aperture; an eyelet in said aperture to receive an assembly rod; and a helical spring standing in said recess and anchored to said eyelet.

45 5. An element to be assembled in a journal box with other similar elements comprising, in combination: a form-retaining plate of absorbent material; said plate having an aperture and a recess cut in its material terminating adjacent

said aperture; an eyelet in said aperture to receive an assembly rod; a helical spring standing in said recess and anchored to said eyelet; and means to retain said spring from lateral displacement from said recess.

50 6. An element to be assembled in a journal box with other similar elements comprising, in combination: a form-retaining plate of absorbent material having an aperture and a recess extending from an edge thereof to a location adjacent said aperture; an eyelet fixed in said aperture; a rigid element embedded in said plate extending to a position adjacent a journal contacting edge thereof and rigidly supported from said eyelet; and a spring seated in said recess and anchored to 15 said eyelet.

7. An element to be assembled in a journal box with other similar elements comprising, in combination: a form-retaining plate of absorbent material having an arcuate journal bearing surface upon an edge thereof, an aperture therethrough and a recess extending from an edge opposite said surface to a position adjacent said aperture; a wooden plate embedded in said absorbent plate and having an aperture in alignment with the first named aperture; an eyelet secured in said aperture; and a helical spring seated in said recess and anchored to said eyelet.

8. A lubricating packing for journal boxes comprising, in combination: a mass of felted absorbent material having a journal contacting surface presenting a great preponderance of fiber ends to the journal; the dimension of said mass perpendicular to said surface being less than the depth of a journal box below the journal; a plurality of spaced projections of absorptive material carried by said mass to contact the bottom of the journal box; a plurality of springs embedded in said mass, extending to abut the bottom of a journal box and operable to press said surface against a journal.

30 35 9. A lubricating packing for journal boxes comprising, in combination: a mass of felted absorbent material having a journal contacting surface presenting a great preponderance of fiber ends to the journal; the dimension of said mass perpendicular to said surface being less than the depth of a journal box below the journal; a plurality of spaced projections of absorptive material carried by said mass to contact the bottom of the journal box; a plurality of rigid, non-metallic plate elements embedded in and anchored to said mass and presenting edges at said contacting surface; a plurality of springs embedded in said mass, abutting said plate elements and extending to 40 45 50 55 the bottom of the box.

10. An element to be assembled in a journal box with other similar elements comprising, in combination: a form retaining plate of absorbent material having an aperture, a recess cut in its material terminating adjacent said aperture and a socket in a journal contacting edge; an eyelet in said aperture to receive an assembly rod; a helical spring standing in said recess and anchored to said eyelet; and a pin of rigid, non-metallic material seated in said socket to be pressed into contact with a journal by action of said spring.

RUDOLPH W. MILLER.
